WELL PUMP

Dee E. Humphrey, Dallas, Tex.

Application October 4, 1940, Serial No. 359,695

5 Claims. (Cl. 103—158)

This invention relates to well pumps and more particularly to pumps for deep oil and artesian wells.

The principal object of the invention is to dispense with heavy and expensive equipment usually employed for pumping wells, including sucker rods, surface equipment such as pumping units, jacks and powers and replace such equipment with a simple, inexpensive and durable reciprocating element, suspended on the tubing string at the bottom of the hole.

Another object of the invention is to provide means for rotating the tubing string as well as means for translating such movement into reciprocating movement for so actuating the working barrel, thereby to elevate liquid through the tubing in successive stages, aided by a series of relatively spaced and conventional valves.

Another object of the invention is to provide means by which any differential speed ratio may be obtained between the rotatable speed of the tubing and the reciprocable speed of the working barrel. For example, rotation of the tubing at the rate of 60 R. P. M. will cause the working barrel to travel approximately 200 inches in effective work and which ratio may be changed by varying several factors in the assembly.

The invention has further advantages in that it produces a continuous swabbing effect on the well; minimizes accumulation of basic sediment, paraffin deposits, emulsion, sand and the like at the bottom of the hole, due to the agitation set up at this point by the action of the working barrel.

The present invention is an improvement on the application for Well pump, filed by applicant August 8, 1940 and which bears Serial Number 351,839.

With the foregoing and other objects in view, the invention has particular reference to certain salient features of construction and arrangement of parts to become manifest as the description proceeds, taken in connection with the accompanying drawing, wherein:

Figure 1 is a view of the invention in vertical section showing one form of power transmission in the well and the means for converting rotary into reciprocating movement for actuating the working barrel.

Figure 2 is a continuation of Figure 1.

Figure 3 is a transverse section on line 3—3 on Figure 1.

Figure 4 is a transverse section, taken on line 4—4 on Figure 1, and

Figure 5 is a detail view in perspective, show-

ing one of the suspension tracers for the working barrel.

Continuing with a more detailed description of the drawing, the reference numeral 1 denotes a well casing, on which is suitably mounted a driving head 2, for rotating a string of upset tubing 3, suspended within the casing 1.

The driving head 2 is shown in the drawing to contain a conventional worm and gear assembly for transmitting rotary movement to the tubing string but in actual practice, a speed reduction mechanism, as set forth in applicant's U. S. Letters Patent No. 2,206,958, issued July 9, 1940, will provide an effective drive for this purpose as well as affording a medium, not unlike that illustrated in Figure 1, for transmitting power to and reducing the speed of the lowermost section 4 of tubing in the string and which section will be described presently.

The gearing in the head 2 as shown consists of a worm gear 5, mounted on bearings 6, upon a boss 7. The squared end 8 of the upper section of tubing extends through a central opening in gear 5 and through a square opening in a block 9, which latter, in turn, rests in a square recess in the gear 5. This arrangement enables gear 5 to rotate the tubing string 3. To drive the gear 5, a worm 10 is mounted on shaft 11 to mesh with the teeth of gear 5 and a V-belt pulley 12 is mounted also on shaft 11 and operated by a motor to rotate shaft 11. Suitable packing 13 surrounds the tubing 3 in the head 2 and is held in place by means of a thrust collar 14.

Suspended by the tubing string 3 is a union 15. This union is provided with a shoulder or ledge 16 which serves as a lower race for ball bearings 17. As an upper race for the balls 17, there is provided a circular plate 18, welded or otherwise suitably secured to the upper ends of guides 19. These guides not only serve to hold the working barrel, to be described presently, against rotation, but function also as a form of anchor and support, supplementing the bearing just described, comprised of elements 16, 17 and 18, thereby alleviating strain of suspension on the tubing string 3.

To the plate 18 is pivoted grips 20, which, under pressure of springs 21, are urged against the walls of casing 1, to hold the guide assembly against any tendency to rotate with the tubing string 3. The plate 18 and consequently the guide assembly is partially suspended upon the ledge 16 of the bearing assembly. A thick walled collar 22 serves to retain the parts of the bearing assembly in proper relationship. The

collar 22 is threaded to receive the reduced end 23 of the union 15.

The lowermost section 4 is a multiple return grooved tubular member, in which the twin grooves are identified by reference character 24 and travelling in these grooves is a pair of diametrically opposed, arcuately shaped tracers 25 having cylindrical bodies 25a for free rotation in the correspondingly circular and diametrically opposed recesses in the working barrel 26 adjacent the top thereof, as shown.

It is apparent that through the medium of the dual tracer arrangement, there is no side thrust on the member 4 to cause the same to be moved out of its true concentric relationship with the working barrel 26, and it is intended that the combined surface of the tracers in contact with the member 4 will embrace at least two-thirds of its circumference at the point of engagement. Moreover, such an arrangement reduces friction between the member 4 and working barrel and lends materially to the amount of load of fluid which the barrel 26 may carry. The tracers 25 are of case hardened steel and in practice have been found to show no appreciable wear under long and hard usage.

In being in opposed relationship in their respective grooves 24 as they are, one tracer 25 will assume an angle exactly opposite to that of the companion tracer in operation, as illustrated in Figure 3 and as the working barrel 26 reaches the end of its travel in either direction, the angularity of the tracers reverses suddenly to allow for the extended or continuous rectilinear travel thereof as compared to and brought about by rotation of the tubing string 3 at the surface.

The guide or anchor members 19 which are vertically disposed and radially spaced ribs, are, as stated, connected to or a part of the plate 18, from which they depend into the well alongside the working barrel 26. While the grips 20 do serve to effectively hold the working barrel against rotation, due to engagement of the lugs 27 against the ribs 19, an added precaution against such rotation is afforded by the fact that the lower ends of the ribs 19 are set in the bottom of the hole. (Figure 2.) By thus resting on the bottom of the hole, some of the weight of the suspended mass is relieved on the tubing and surface support.

In operation, the tubing string 3, carrying the grooved section 4 is run into the casing much in the same manner as tubing is usually done. When power is applied to the pulley 12, worm 10 will rotate gear 5 to revolve the tubing string 3. This will impart rotation to the union 15 and which, in turn, will revolve the tubing section 4. Obviously, rotation of section 4 will cause the oppositely disposed protuberances or tracers 25 to move up or down, depending upon the angle of the grooves in which they are disposed and in moving down, the working barrel 26 is lowered so that it will be submerged in the liquid 38 in the bottom of the well. Fluid will enter the working barrel by lifting ball 28 and when the tracers 25 have reached the lower limit of the groove 24, their relative angles and direction of travel will be reversed and the working barrel 26 will begin to ascend, carrying with it the fluid. As the working barrel continues to rise, the fluid therein will seat the ball 28 in the bottom of the section 4, thereby entrapping the same above the valve. As the operation continues, each fluid load will be successively passed upward to be assumed by the

tubing valve 31, shown in Figure 1, at the lower end of the tubing string 3. It is understood that each tracer operates in its own individual groove and any attempt to reverse their relative positions would result only in locking the parts 4 and 26 together against movement of any kind. When the fluid, elevated by the working barrel reaches the top of the tubing string, it emerges into the driving head 32 and enters a discharge line 33 for transfer to storage.

Manifestly, the construction as shown and described is capable of some modification and such modification as may be construed to fall within the scope and meaning of the appended claims is also considered to be within the spirit and intent of the invention.

What is claimed is:

1. A well pump including in combination with a tubing string in a well, means for rotating said tubing string, a tubular body suspended below said tubing string for common rotation therewith and having continuous twin double helix grooves in its exterior surface, a piston carried by said tubular body, a working barrel held against rotation in which said tubular body operates, a pair of diametrically opposed members connected to said working barrel and disposed in respective grooves of said body to travel therein when said tubing string is rotated, whereby to effect vertical reciprocation of said working barrel and valve means in said working barrel and said tubing string for controlling fluid for upward passage through said tubing string.

2. A well pump including in combination with a tubing string in a well, means for rotating said tubing string, a working barrel, a multiple return grooved tubular member in said working barrel, suspended by said tubing string and rotatable therewith, a piston carried by said tubular member, tracers carried by said working barrel, disposed in diametrically opposed relationship, each operating in a groove of said tubular member to effect extended rectilinear movement of said working barrel when said tubing string is rotated, means to hold said working barrel against rotation and valve means carried by said working barrel and tubing string to elevate fluid from said well through the movements of said working barrel.

3. A well pump including a tubing string and means to rotate said tubing in a well, a tubular member below and rotated by said tubing having twin double helix grooves in its outer surface, a piston on said tubular member, a valve in said tubular member, a working barrel concentrically embracing said tubular member, guide means concentrically embracing said working barrel and arranged to hold the same against rotation, a pair of tracers carried by said working barrel each arranged to travel in a groove of said tubular member to cause said working barrel to move rectilinearly in continuous motion when said tubing is rotated, to elevate fluid from said well.

4. A well pump including a tubing string, means for rotating said tubing string, a multiple return grooved tubular member suspended by said tubing and rotated thereby, a piston on said tubular member, valves in said tubing, a working barrel surrounding said tubular member, diametrically opposed tracers carried by said working barrel each arranged to travel in a groove of said tubular member and capable of reversal at either end of said tubular member to effect reciprocation of said working barrel and whose

joint areas in engagement with said tubular member will equal at least two-thirds of the circumference thereof at the point of engagement and valve means in said working barrel to effect transfer of well fluid above the valves in said tubing string.

5. A well pump including a tubing string and means for rotating the same in a well, valves in said tubing string, a working barrel below and suspended partially by said tubing string and held against other than extended rectilinear motion and return, a valve in the lower end thereof,

an elongated hollow body suspended in said working barrel by and rotated through the medium of said tubing string, a piston thereon, said body having multiple return grooves in its exterior surface, a valve therein, a pair of tracers carried by said working barrel each being disposed in a groove of said body in diametrically opposed relationship to effect extended rectilinear motion of said working barrel when said tubing string is rotated, to elevate fluid from said well through said valves.
